(57) **CLAIM**

The ornamental design for a weather station, substantially as shown and described.

DESCRIPTION

FIG. 1 is a front perspective view of a weather station showing our new design;

FIG. 2 is an alternative perspective view of a weather station showing our new design and rotated from FIG. 1;

FIG. 3 is a left side elevation view of a weather station shown in FIGS. 1 and 2;

FIG. 4 is a right side elevation view thereof;

FIG. 5 is a rear elevation view thereof;

FIG. 6 is a top plan view thereof; and,

FIG. 7 is a bottom plan view thereof.

The black borders shown in FIGS. 3–5 do not form part of the claimed design but are included to aid in comprehending shape of our new design.
